(57) **CLAIM**

The ornamental design for a sorter, as shown and described.

DESCRIPTION

FIG. 1 is a perspective view of a sorter showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of the sorter of FIGS. 1-7 with the lines visible through the translucent surfaces being removed for clarity;

FIG. 9 is a front view thereof;

FIG. 10 is a rear view thereof;

FIG. 11 is a right side view thereof;

FIG. 12 is a left side view thereof;

FIG. 13 is a top plan view thereof; and,

FIG. 14 is a bottom plan view thereof.

The broken line showing of the four support feet of the sorter is for environmental purposes only and forms no part of the claimed design.
